UNITED STATES PATENT OFFICE.

JULIUS SWANBERG, OF CHICAGO, ILLINOIS, ASSIGNOR TO SWANBERG MANUFACTURING COMPANY, OF CHICAGO, ILLINOIS, A CORPORATION OF ILLINOIS.

PENCIL.

Application filed May 23, 1921. Serial No. 471,537.

This invention relates to a pencil and particularly to a metallic pencil comprising a small number of inexpensive, easily assembled parts. The depletion of the supply 5 of suitable wood for pencils and the trouble occasioned by sharpening the same has necessitated the provision of metallic pencil casings, and these casings are preferably provided with a mechanism for moving additional lead into writing position after a 10 protruding portion thereof has been used. In order, however, that these metallic pencils be commercially successful it is necessary that they be cheap, reliable and not 15 easily injured. It is also desirable that an arrangement be provided whereby new leads may be conveniently and quickly inserted for use in the pencil.

It is an object of the present invention to 20 provide a pencil wherein a lead guiding tube is rotatably mounted in the pencil casing.

It is a further object of this invention to 25 provide a pencil having a relatively rotatable lead guiding tube extending axially of the pencil casing and having a chamber for extra leads formed between the tube and the casing.

It is a further object of this invention to 30 provide a pencil wherein lead guiding means extend axially through the pencil casing and protrude from the lower end thereof.

It is an important object of this invention to 35 provide a pencil which may be conveniently assembled and which consists entirely of parts which may be economically manufactured.

Other and further important objects of 40 this invention will be apparent from the disclosures in the specification and the accompanying drawings.

The invention (in a preferred form) is 45 illustrated in the drawings and hereinafter more fully described.

On the drawings:

Figure 1 is a side elevation of a pencil embodying the principles of this invention.

Figure 2 is an enlarged section on the line 2-2 of Figure 1.

Figure 3 is a slightly enlarged fragmentary elevation of a part of the lead feeding mechanism.

Figure 4 is a detail plan view of the connecting means on the lead feeding plunger.

Figure 5 is a fragmentary side elevation

of the connecting means on the lead feeding plunger.

Figure 6 is an enlarged fragmentary section showing the method of securing the lead guiding tube in the pencil casing. 60

Figure 7 is a slightly enlarged section on the line 7-7 of Figure 2, and

Figure 8 is a slightly enlarged section on the line 8-8 of Figure 2.

As shown on the drawings:

The outside of the pencil of this invention preferably comprises a tubular casing 1, which is reduced at one end to form a conical point 2 and the other end of which is formed inwardly to afford an internal bead 70 3 which is adapted to springingly engage in a peripheral groove in a cap 4, this springing engagement being allowed by slots 5 in the casing 1 extending downwardly for a short distance from said bead 3. The 75 outer end of the cap 4 is recessed to receive a suitable eraser 7 which is frictionally secured therein and the inner end of said cap is recessed and has frictionally secured therein the end of a lead guiding tube 8 80 which extends axially of the casing and protrudes from the conical point 2 thereof. The lower end of said lead guiding tube 8 is rotatably secured in said conical point 2 by the engagement of the annular flange 85 9 on the inside of the casing near the lower end of said point with an annular recess in the tube. The flange 9 and the recess in the tube 8 are so proportioned that the portion of said tube which protrudes from 90 the point is flush with the outer walls of the pencil casing, and said protruding portion is slotted at 10 and bent slightly inwardly to frictionally engage a lead 11 which protrudes therefrom and which extends upwardly into the tube 8. Mounted inside the tube 8 and abutting the inner end of the lead 11 is a wire plunger 12 which is provided with a curved transverse projection

13 which extends outwardly through a longitudinal slot 14 in said tube and which is engaged between the coils of a helical spring 15 mounted in the casing 1 above the conical point 2 and held by its own frictional engagement with the inside of said casing 105 from movement relative thereto. The spring 15 in effect provides a feeding screw which is engaged by the projection 13 on the wire plunger 12, and since said spring is frictionally held from movement relative 110

to the casing it is apparent that rotation of the cap 4 and the tube 11 will cause said plunger to move longitudinally in the tube 8 and consequently force the lead 11 outwardly or move inwardly to allow the insertion of a new lead depending upon the direction of rotation of the cap and the tube. A chamber for extra leads is afforded inside the upper end of the casing 1 by securing a disk or washer 16 to the tube 8 above the upper end of the spring 15.

The operation of the pencil of this invention is very simple for when the protruding point of the lead 11 becomes worn it is only necessary to rotate the cap 4 to cause the plunger 12 to force the lead outwardly from the tube 8 which also rotates with said cap. New leads may be inserted in the pencil by rotating the cap 4 in the opposite direction until the plunger 12 is in the extreme inward position and subsequently forcing the lead into the tube 8 through the slotted protruding point thereof. Since the cap 4 is only frictionally held in contact with the casing 1 it may be easily removed to afford access to the extra lead compartment above the disk 16.

It will be noted from the foregoing specification that the pencil of this invention is composed of parts which may be economically manufactured and conveniently assembled. The provision of the rotatable lead guiding tube 8 affords a single connec-

tion between the lead feeding mechanism and the rotatable cap, and by extending said tube 35 through the conical point of the pencil the necessity of a special lead-engaging point for the pencil is obviated. Said tube 8 is extended through the conical point 2, the opening through which is originally of 40 greater diameter than the tube 8, and the casing is subsequently swaged or spun inwardly to reduce this diameter so that the flange or inward projection 9 thereon is engaged in the recess in the tube 8. 45

I am aware that numerous details of construction may be varied through a wide range without departing from the principles of this invention, and I therefore do not purpose limiting the patent granted otherwise than necessitated by the prior art. 50

I claim as my invention:

A pencil, comprising an outer casing having a conical tip and a slotted internally beaded top, a lead guiding tube extending 55 the length of said casing and swivelly held against relative axial movement in the conical tip thereof and a closure member resiliently held for relative rotation by said internally beaded top and in frictional non- 60 rotative engagement with the end of said lead guiding tube.

In testimony whereof I have hereunto subscribed my name.

JULIUS SWANBERG.
